DOOR HANGER

Leonard E. Johnson, Jr., Rte. 4, Oakland Ave.,
Elkhart, Ind.

Filed June 18, 1958, Ser. No. 742,814

5 Claims. (Cl. 16—87)

The present invention relates generally to sliding doors and more particularly to hangers for supporting such doors in an overhead track.

It is desirable that the door be easily installed in and easily removed from its operative position; and that it be easily and securely adjusted to provide proper clearances between the door and the floor or surface below the door.

In the building trade it is customary to secure the hanger to the door by wood screws which may be removed to detach the door or relocated to adjust the door. Repeated detachments of the door, however, cause the screws to become loosened resulting in misadjustment or an undesired detachment of the door. Repeated relocations of the screws to adjust the door, of course, cause disfigurement of the door.

In the door hanger of the present invention a base member is adapted to be permanently fastened to the door. A hanger member, having a roller adapted to ride in an overhead track, is adjustably secured to the base member by two screws. One of the screws threadedly engages an integral part of the base member and is disposed in an open ended slot formed in the hanger member. The other of said screws threadedly engages a non-circular insert member disposed in a complementary shaped opening in the base member. The hanger member may be readily detached from the base member by loosening the first mentioned screw a few turns sufficient to permit the hanger member to be tilted whereby the insert member may be removed from the base member opening and the first mentioned screw may be removed from the open ended slot thereby completing the detachment. The second screw, holding the insert member to the hanger member, is undisturbed in the detaching process whereby upon reassembly of the hanger and base members the adjustment of the door is undisturbed. Adjustment of the door may be easily accomplished, however, by loosening both screws and retightening them when the door is in proper position.

It is an object of the present invention to provide in a door hanger means whereby at least a portion of the hanger may be readily attached and detached without affecting the adjustment thereof.

It is a further object of the invention to provide a door hanger which may be readily detached and/or adjusted and which is relatively simple, reliable and inexpensive to manufacture.

It is a still further object of the invention to provide an improved roller and axle for a door hanger.

These and other objects and advantages of the present

2

invention will become apparent from the following detailed description taken in connection with the accompanying drawings wherein:

Figure 1 is a partial elevation view of a sliding door suspended by a door hanger embodying the present invention;

Figure 2 is a perspective view of the door hanger and a portion of the track shown in Figure 1;

Figure 3 is a rear view of the door hanger shown in Figure 2;

Figure 4 is a perspective view of the insert member shown in Figure 3; and

Figure 5 is a sectional view taken along line 5—5 of Figure 2.

Referring now to the drawings and more particularly to Figure 1, numeral 20 designates a frame assembly including a cross header member 22 and vertical frame members 24 and 26. A metal track 28 is secured to header 22 by suitable means, not shown. Track 28 is formed with a pair of spaced parallel rails 34 and 36 having a generally U-shaped cross section.

A door 38 is shown suspended from track 28 by a door hanger 40 which comprises a base member 42, an insert member 44 and a hanger member 46. Base member 42 is formed with a pair of spaced ears 48 which are adapted to engage the top of the door 38 to position the base member thereon. The base member 42 is secured to the door 38 by suitable screws 50 which pass through holes 52 formed in the base member.

The insert member 44 is cut out of the base member 42 leaving a non-circular opening formed therein. A turned up, substantially rectangular portion 56 is formed on the insert member for a purpose to be described later.

The hanger member 46 is formed with an opened ended slot 58 and a closed ended slot 60. An offset bracket 62 is formed on member 46 and is adapted to extend upwardly over the top of the door 38 intermediate the edges thereof. An axle 64 is secured at one end 66 to bracket 62 and is formed with a reduced shoulder 68 adjacent end 66 and a substantially constant bearing portion 70 from shoulder 68 to the unsecured end 72 thereof. A nylon roller 74 is rotatably mounted on axle 64 and is provided with a flange 76 for engagement with shoulder 68 whereby axial movement of the roller is prevented.

A screw 78 having a head overlapping slot 58 engages a hole 80 in base member 42 to adjustably clamp hanger member 46 to the base member. A screw 82 having a head overlapping slot 60 engages a hole 84 in the insert member 44 to adjustably clamp the hanger member 46 to the insert member. Screws 78 and 82 may be of the sheet metal type and the holes 80 and 84 may then be unthreaded; or the holes 80 and 84 may be threaded and the screws 78 and 82 may then be of the machine type.

Each door 38 is normally provided with two door hangers 40 spaced along the top edge thereof. The base member 42 is positioned on the door by means of ears 48 and is secured thereto by means of screws 50. The roller 74 on the hanger member 46 is inserted in the track 28 through an opening 86 between the track and the vertical frames 24 or 26. While only one door is shown in Figure 1, it is to be understood that in actual practice two doors could be mounted on track 28 with one pair of rollers on one door engaging rail 34 and a second pair of rollers on a second door engaging rail 36.

A door is placed in the opening under the track and the hanger member 46 positioned over the base member on the door. The insert member 44 which is clamped to the hanger member is positioned in opening 54 in the base member and screw 78 is inserted in hole 80 in the base member to complete the attachment of the base and hanger members. Screws 78 and 82 permit the door to be adjusted vertically to provide the desired clearance between the bottom of the door and the floor or other surface below the door.

The turned-up portion 56 on insert member 44 projects into slot 60 to restrain the insert member against rotation when it is out of opening 54. This construction permits the insert member to be easily adjusted prior to assembly with the base member, if desired.

To detach the hanger member 46 from the base member 42, it is only necessary to loosen screw 78 a few turns whereby the insert member may be lifted from opening 54 and the screw 78 removed through the open end of slot 58. Upon reassembly, the insert member 44 is repositioned in opening 54 and the screw 78 tightened whereby the clearance established prior to the detachment is preserved upon attachment. The insert member 44 when in opening 54 is coplanar with the base member whereby the thickness of the door hanger 40 is kept to a minimum. The screws 78 and 82 are located to clear the top of the door and work entirely in metal so that they may be repeatedly adjusted and/or removed without the disadvantages associated with screw adjustments in wood.

While only one embodiment of my invention has been shown and described various changes and modifications may be made without departing from the spirit of the invention.

I claim:

1. A door hanger for a door adapted to be suspended from a track comprising a plate-like base member having a non-circular opening formed therein and being adapted to be secured to one side of said door adjacent the upper edge thereof, a pair of spaced ears formed on said base member for engagement with the upper edge of said door to position said base member thereon, an insert member removably mounted in said opening, said insert member being shaped complementary to said opening, a hanger member formed with a pair of longitudinally extending slots, at least one of said slots being open at the lower end thereof, a screw overlapping the open ended slot and extending therethrough and threadedly engaging said base member to clamp said hanger member to said base member, a screw overlapping the other of said slots and extending therethrough into threaded engagement with said insert member to clamp said hanger member to said insert member, said hanger member and said insert member being detachable from said base member as a unit when said first-mentioned screw is loosened whereby said hanger member may be separated from said base member thus removing said insert member from said opening and thereby permitting the hanger member to be moved longitudinally passing said first mentioned screw through the open end of said slot, an axle secured at one end to said hanger member and extending substantially perpendicular to the plane of the door when said hanger member is clamped to said base member, said axle being formed with a shoulder adjacent said hanger member and with a substantially constant diameter bearing portion from said shoulder to the unsecured end thereof, and a roller adapted for engagement with said track rotatably mounted on said axle and having a flange formed thereon to extend between said shoulder and said hanger member to restrain said roller from axial movement.

2. A door hanger for a door adapted to be suspended from a track comprising a plate-like base member having a non-circular opening formed therein and being adapted to be secured to one side of said door adjacent the upper edge thereof, an insert member removably mounted in

said opening, said insert member peripherally engaging at least a portion of said base member surrounding said opening whereby translatory and rotational movement of said insert member in the plane of said base member is prevented, a hanger member formed with a pair of longitudinally extending slots at least one of which is provided with an open lower end, a screw overlapping the open ended slot and extending therethrough into threaded engagement with said base member to adjustably clamp said hanger member to said base member, a screw overlapping the other of said slots and extending therethrough into threaded engagement with said insert member to clamp said insert member to said hanger member said hanger and insert members being detachable as a unit from said base member when said first mentioned screw is loosened thereby permitting said hanger member to be separated from said base member and thus removing said insert member from said opening whereby the hanger member may be moved longitudinally passing said first mentioned screw through the open end of said first mentioned slot to complete the detaching operation, and a roller mounted on said hanger member for engagement with said track.

3. A door hanger for a door adapted to be suspended from a track comprising a plate-like base member adapted to be secured to said door and having an opening formed therein, an insert member removably mounted in said opening and adapted for peripheral engagement with at least a portion of the base member surrounding said opening whereby longitudinal movement of the insert member in the plane of said base member is prevented, a hanger member formed with first and second slots therein, a screw mounted in said base member and having a portion overlapping said first slot to longitudinally adjustably clamp said hanger member to said base member, a screw mounted in said insert member and having a portion overlapping said second slot to longitudinally adjustably clamp said hanger member to said insert member, an ear formed on said insert member and disposed in said second slot to prevent rotation of said insert member relative to said hanger member, said insert and hanger members being detachable as a unit from said base member whereby upon reattachment the longitudinal adjustment of the hanger member with respect to the base member is preserved when the insert member is remounted in said opening, and a roller mounted on said hanger member for engagement with said track.

4. A door hanger for a door adapted to be suspended from a track comprising a plate-like base member adapted to be secured to said door and having an opening formed therein, an insert member removably mounted in said opening and peripherally engaging at least a portion of said base member surrounding said opening and being of substantially the same thickness as said base member, a hanger member having first and second longitudinally extending slots formed therein, a screw overlapping said first slot and extending therethrough into threaded engagement to adjustably clamp said hanger member to said base member, a screw overlapping said second slot and passing therethrough into threaded engagement with said insert member to adjustably clamp said hanger member to said insert member said insert and hanger members being detachable as a unit from said base member whereby upon reattachment the longitudinal adjustment of the hanger member with respect to the base member is preserved when the insert member is remounted in said opening, and a roller mounted on said hanger member for engagement with said track.

5. In a door hanger for a door adapted to be suspended from a track a plate-like hanger member adapted to be secured to said door, an axle secured at one end to said hanger member and extending therefrom substantially perpendicular to the plane of the door when said hanger member is secured to said door, said axle having a reduced diameter portion extending axially a prede-

terminated distance from said one end and a greater substantially constant diameter portion extending axially from said reduced diameter portion to the free end of said axle, and a roller adapted for engagement with said track and having an axially extending bore formed therein with a radially inwardly extending flange formed at one end of said bore, said roller being rotatably mounted on said axle with said bore in bearing engagement with the greater diameter portion of said axle and said flange in engagement with the reduced diameter portion of said axle whereby axial movement of said roller on said shaft in either direction is restrained

through axial engagement of said flange with said hanger member in one direction and the greater diameter portion of said axle in the other direction.
